UNITED STATES PATENT OFFICE.

FRANK J. STEVENS, OF ROCHESTER, NEW YORK, ASSIGNEE, BY MESNE ASSIGNMENTS,
TO LOCKE INSULATOR CORPORATION, OF BALTIMORE, MARYLAND, A CORPORA-
TION OF MARYLAND.

CEMENTLESS STRAIN INSULATOR.

1,412,759.

Specification of Letters Patent. Patented Apr. 11, 1922.

Application filed June 18, 1917. Serial No. 175,270.

To all whom it may concern:

Be it known that I, FRANK J. STEVENS, of Rochester, in the county of Monroe and State of New York, have invented certain new and useful Improvements in Cementless Strain Insulators; and I do hereby declare the following to be a full, clear, and exact description of the same, reference being had to the accompanying drawings, forming a part of this specification, and to the reference-numerals marked thereon.

My invention has to do with strain insulators of the general type employed for conductors of high tension currents and embodying generally a series of insulating units assembled one upon the other and the purpose of the present construction is to afford such a connection between adjacent insulator units as to obviate the necessity of using any cementitious attaching material. A further purpose is to provide means for securing one insulator in proper relation with another by a metallic connecting device which is separable, and held in place merely by a locking engagement or contact. An additional object is to afford a reasonably economical structure, which permits of ready assembling. To these and other ends the invention consists in certain improvements and combinations of parts, all as will be hereinafter more fully described, the novel features being pointed out in the claims at the end of the specification.

In the drawings:

Figure 1 is a side elevation showing a strain insulator constructed in accordance with my invention;

Figure 2 is a vertical sectional view;

Figure 3 is plan view of an insulating unit forming a part of my improvement;

Figure 4 is a bottom plan view of the same;

Figure 5 is an enlarged sectional view showing the parts in the position of assembling, and

Figure 6 is a horizontal sectional view taken substantially on a line 6^a—6^a of Figure 2.

Similar reference numerals in the several figures indicate the same parts.

In the illustrative embodiment shown, I have disclosed a usual form of petticoat type of insulating member or unit designated generally by 1, which is provided with a pair of

exteriorly arranged sockets or recesses 2 having curved walls 3 formed by a substantially circular retaining portion 4. Arranged interiorly of the insulating member is a pair of recesses or sockets 5 having curved walls 6 formed by a circular retaining portion 7. The exterior sockets 2 extend at right angles to the interior sockets 5, the two pairs of recesses or sockets being so disposed as to receive curved arms forming parts of connecting devices which serve to unite the insulating unit with those on opposite sides of it, in accordance with the usual practice in this art of employing a series of insulating units in juxtaposed relationship.

Each connecting device comprises a pair of independent members, each of which includes a pair or set of oppositely extending curved arms 6^a and 6^b, and 7^a and 7^b. The curved arms 6^a and 7^a form one pair of jaws and correspondingly the curved arms 6^b and 7^b form another pair of jaws, the said pairs of jaws being connected as hereinafter set forth. Lugs 6^c and 7^c are formed at the central portions of the members and serve as a means for connecting them together. The members of the connecting device are applied to the two adjacent insulator units in the manner shown in Figure 5, with the curved arms of each member engaging respectively one of the interior recesses or sockets of the one unit and one of the exterior recesses or sockets of the other unit. When thus positioned, the members of the connecting device are joined by a bolt or pin engaging openings in the lugs at the central portions and securely attached as shown in Figure 2. The two members of the connecting device are thus connected together, and serve to unit two insulating units so that they can be readily transported without possibility of the porcelain of one getting into contact with the porcelain of the other and becoming damaged. The structure affords an extremely strong and durable connection under actual service conditions, readily shedding water, and affording no water retaining pockets, at the same time permitting the removal of one or more of the connecting devices and the corresponding porcelain units if this should at any time be desirable. Insulating units of this type, as well as the connecting device, are comparatively simple and economical to

manufacture, and also afford great facility in their assembling.

The essential characteristic of my improvement may be carried out in ways other than that specifically set forth, and the present disclosure is by way of example of one way of adapting the improvement, and not in any sense as restricting the invention to any particular structure. I believe it new to provide an insulating unit with pairs of interior and exterior recesses, to receive corresponding pairs of arms of a connecting device, formed in two or more parts which are suitably secured together to retain the insulator, and at the same time are separable if necessary, and the claims of this application are intended to cover any modifications or departures incorporating such idea.

I claim as my invention:

- 20 1. In a strain insulator, the combination with an insulating unit having an undercut attaching head, and a connected member, of a detachable connecting device comprising two pairs of relatively movable jaws, the jaws of either pair being adapted to engage the said attaching head, and the other pair of jaws being adapted to engage the said connected member, one jaw of each pair being rigidly joined to the corresponding jaw of the other pair to constitute a set, and means for connecting the two sets.
- 25 2. In a strain insulator, the combination with insulating units each having an undercut attaching head, of a detachable connecting device comprising two pairs of pivoted jaws, the jaws of either pair being adapted to engage either attaching head, one jaw of each pair being integrally connected together to constitute a set, and means for pivoting connecting the said two sets.
- 30 3. In a strain insulator, the combination with an insulating unit having an undercut attaching head, of a detachable connecting device comprising spaced pairs of jaws, one jaw of each pair of jaws being connected to a corresponding jaw of the other pair of jaws, either pair of said jaws being adapted to engage with said attaching head, and

means pivotally connecting one jaw of each pair to the other jaw of the same pair, said means being common to both pairs of jaws whereby one of said pairs of jaws is adapted to actuate the other pair of jaws reversely in opening or closing.

4. In an insulator, the combination with an insulating unit having an undercut attaching head, of a detachable connecting device comprising two pairs of spaced jaws, each jaw of each pair of jaws being integral with the corresponding jaw of the other pair of jaws and forming a hook-shaped member, either pair of jaws being adapted to engage with said attaching head, and means for pivotally connecting one of said hook-shaped members to the other whereby one of said pairs of jaws is adapted to actuate the other pair of jaws reversely in opening or closing.

5. In a strain insulator, the combination with insulating units each provided with a projecting attaching head, said heads being circular in cross section, of means for connecting said units, said means comprising a pair of hook-shaped members each of which is adapted to engage the attaching heads on both of said units, and pivot means extending through said hooks and adapted to prevent separation thereof whereby the disengagement of said hooks from said attaching heads is prevented.

6. In a strain insulator, the combination with a member having a curved surface, of an insulating unit provided with an attaching head circular in vertical cross section, and means for operatively connecting said insulating unit to said member, said means comprising a pair of hook-shaped members each having spaced arcuate faces, said faces being adapted to engage the curved surface of said member and the head on said insulating unit, and means for pivotally connecting the said hook-shaped members at a point intermediate the insulating unit and the said member.

FRANK J. STEVENS.
